BOTTLE

Donald E. Dailey, Evansville, Ind., assignor to John H. Breck, Inc., Springfield, Mass.

Filed Dec. 26, 1962, Ser. No. 72,941

Term of patent 14 years

(Cl. D58—8)

FIG. 1 is a front elevation of a bottle embodying my new design, the rear being a mirror image thereof;

FIG. 2 is a side elevation thereof, the opposite side being of identical appearance;

FIG. 3 is a top plan view thereof; and

FIG. 4 is a sectional view taken on line 4-4 of FIG. 1.

The dominant features of my design reside in a bottle having a substantially frusto-conical shape which is elliptical in cross section, in combination with an oval depression on each side as shown.

I claim:

The ornamental design for a bottle, as shown and described.
